UNITED STATES PATENT OFFICE.

EARL R. HAMILTON, OF PEKIN, INDIANA.

APPARATUS FOR THE TREATMENT OF HYDROCARBON COMPOUNDS.

Application filed November 17, 1924. Serial No. 750,346.

This invention, which is an improvement upon the subject matter of my co-pending application Serial No. 672,099, filed Nov. 1, 1923, (Patent No. 1,614,791, Jan. 18, 1927,) 5 and is embraced by certain of the claims thereof, relates to apparatus for the treatment of hydrocarbon compounds for the purpose of obtaining therefrom hydrocarbons of a different nature from the compounds treated and is particularly adapted for the treatment of heavy hydrocarbon distillates and residues for the purpose of obtaining therefrom hydrocarbon compounds of low boiling points and high volatility 15 such as motor fuel or gasoline.

One of the principal objects of the invention is to provide an apparatus which is capable of either continuous or intermittent operation, as well as one which may be operated at either atmospheric pressure or at 20 higher pressures.

Another object of the invention is to provide an apparatus of the above described character of the cylindrical still type in 25 which provision is made to gradually heat the hydrocarbon compounds, to make the compounds pass along a definite path through the apparatus, to keep the charge in motion by gravity, to keep the compounds 30 in the apparatus for a definite length of time, and to heat them in a uniform manner for a uniform period of time assuring uniform products.

A further object of the invention is to 35 provide an apparatus of the character described in which the low boiling point constituents of the hydrocarbon compounds are vaporized progressively.

A still further object of the invention is 40 to provide an apparatus of the continuous still type, which may be used in connection with a reflux condenser in conjunction with means for the return of the distillate from the condenser to a point in the still where 45 the temperature of the charge corresponds to the temperature of the distillate returned.

An additional object of the invention is to 50 provide an apparatus of the character described in the form of an externally heated container in which the hydrocarbon compounds may be subjected to cracking temperature and the low boiling point constituents collected as distillates or the vapors retained and the whole mass of hydrocarbons allowed to pass from the apparatus to 55

be separated by distillation in separate apparatus.

A still further object of the invention is to provide an apparatus for the treatment of hydrocarbon compounds, which apparatus 60 includes a container capable of being operated as an externally heated still or as a reaction chamber in which heated hydrocarbon compounds are fed and react without further application of heat. 65

According to the invention, the part of the apparatus in which the hydrocarbon compounds are treated, consists of an outer container in which is removably placed an inner container, which is partitioned from its 70 center outward and also transversely into a plurality of communicating cells, so that the hydrocarbon compounds pass through a sinuous course through the inner container. The construction of the inner container and 75 its arrangement within the outer container constitutes the principal novel features of the invention, although as will hereinafter appear, the invention possesses other novelty. 80

A more complete understanding of the invention will be obtained from the following description taken in connection with the accompanying drawings which form a part of this specification, and in which:— 85

Fig. 1 is a horizontal sectional view of a cylindrical still constructed in accordance with the principles of the present invention;

Fig. 2 is a vertical sectional view of the 90 still taken substantially along the line 2—2 of Fig. 1;

Fig. 3 is a transverse sectional view of the still, taken substantially on the plane indicated by the line 3—3 of Fig. 1; 95

Fig. 4 is an end view of a portion of the removable end of the still;

Fig. 5 is a diagrammatic view partly in section and partly in elevation of a still such as shown in Figs. 1 to 4 inclusive, set up together with other apparatus for the treatment of hydrocarbon compounds in accordance with the invention; 100

Fig. 6 is a diagrammatic view, partly in section and partly in elevation, illustrating 105 the manner in which the still such as shown in Figs. 1 to 4 inclusive, may be set up for use as a reaction chamber;

Fig. 7 is a vertical longitudinal sectional view, partly in elevation, of another type of 110

cylindrical still embodying features of the present invention; and

Fig. 8 is a transverse sectional view of the still shown in Fig. 7, said view being taken on the plane indicated by the line 8—8 of Fig. 7.

Referring more particularly to the drawings, and for the present especially to Figs. 1, 2, 3 and 4, it will be seen that the numeral 1 designates the hereinbefore referred to outer container of the apparatus. This of course is made of metal of a proper thickness and is preferably of cylindrical form, being closed at its ends by heads 2 and 3. As shown, the head 2 is fixed, but the head 3 is removable, being held in position by means of bolts 4 and making a liquid-tight joint by reason of the gasket 5.

The inner container which is arranged within the outer container 1 is composed of a plurality of receptacles disposed one within the other and having all of their walls arranged in spaced relation. In the present instance, three of these receptacles are shown, being represented by the numerals 6, 7 and 8, but it will be understood that any number of the receptacles may be used. Inasmuch as the receptacles comprising the inner container are disposed one within the other and have their walls equally spaced, it may be said that such receptacles are concentrically arranged.

Extending longitudinally through the receptacles 6, 7 and 8 so as to divide each of these receptacles in half, is a vertical partition 9. A part of this partition 9 is extended downwardly from the lower side of the receptacle 8 and rests upon the bottom of the outer container 1. Still another part of the partition 9 projects beyond the end wall of the receptacle 8 to form a fluid-tight joint with the web 9' formed on the inside of the fixed head 2 of the outer container 1. Splice plates 10 disposed on opposite sides of the partition 9 and web 9' at their abutting edges, complete the fluid-tight joint between these parts. In order to provide a fluid-tight joint between the lower edge of the partition 9 and the bottom of the outer container 1, molten lead is poured or run into the bottom of the container 1 on opposite sides of the partition 9. This lead being non-miscible with the oil acts as a lute at the points 11 and provides the fluid-tight joint. When removed, the joint is broken so that the inner container as a whole may be withdrawn from the outer container.

One of the elements for supporting the inner container within the outer container is a rail or I-beam which is secured along the top of the outer container. This I-beam is designated by the numeral 12 and by reference to Figs. 2 and 3, it will be seen that its opposite sides receive the rollers 13 of hangers 14 which extend above the inner

container, being secured at suitable points to the central vertical partition 9. When the head 3 of the outer container 1 is removed and fluid-tight joints between the two containers are broken, the inner container 70 may be slid out of the open end of the outer container.

The receptacles 6, 7 and 8 constituting the inner container are divided into a plurality of cells by means of transverse partitions 75 15. The various partitions and walls of the receptacles 6, 7 and 8 are provided with openings or apertures 16 so that the cells communicate one with another. As will hereinafter appear, the hydrocarbon compounds to be treated in the still are introduced into one of the cells of the inner receptacle 6. They then pass into another cell and so on, ultimately passing through all of the cells of all of the receptacles 6, 7 80 and 8. In order that the course of the hydrocarbon compounds may be understood, the cells of the receptacle 6 are numbered successively from 6^a to 6ⁱ according to the course taken by compounds in passing through this receptacle. In a similar manner, the cells of the receptacle 7 are numbered from 7^a to 7ⁱ and those of the receptacle 8 from 8^a to 8ⁱ. From this system of numbering, it will be understood that the 95 compounds are introduced into the cell 6^a. From there, they pass into the cell 6^b and then successively through all of the cells of the receptacle 6 to the cell 6ⁱ. From the cell 6ⁱ they pass into the cell 7^a and then successively through all of the cells of the receptacle 7 to the cell 7ⁱ. From the cell 7ⁱ the compounds pass into the cell 8^a and through all of the cells of the receptacle 8, finally arriving at the cell 8ⁱ, from which they pass 100 into the space between the outer container 1 and the inner container. The aperture or opening through which the hydrocarbons pass from the receptacle 8 into the space between the outer container and the inner container, is located at the rear end of the inner container, on one side of the partition 9, so that the compounds in order to reach the outlet pipe 17 disposed on the opposite side of the partition 9, must pass entirely around the inner container and portion of the partition 9 which is disposed between the inner container and the outer container.

From Figs. 2 and 3 of the drawings, it will be seen that the openings or apertures 120 16 in the partitions and walls of the inner container, are arranged in staggered relation at the upper and lower portions of the cells, so that the compounds will take a zig-zag course in passing through the series of 125 cells. For instance, the compounds will pass downwardly through one cell and upwardly through the next, and so on through the entire series.

The means for introducing the hydrocar- 130

bon compounds into the cell 6^a of the inner container consists of a pipe 18 which passes through the upper side of the outer container 1. The hereinbefore described pipe 17 for conveying away the hydrocarbon compounds from the still, passes through the closure plate for an opening or passage 19. This opening 19 is disposed at the lower portion of the fixed head 2 of the outer container 1 on one side of the end portion of the partition 9, and arranged on the other side of the partition at the lower portion of the head 2 is an opening 20 similar to the opening 19 and closed by a suitable closure plate. The lower portion of the removable head 3 of the container 1 is provided with an opening 21 closed by a closure plate 22, through which passes a valved pipe 23 capable of being used for removing the lead used 20 as a lute. In addition to the openings 19 and 20, the fixed head 2 of the outer container 1 is provided with an opening 24 closed by a closure plate 25. Fitted to the upper side of the outer container 1 is a pipe 26 by which the vapors formed in the still 25 may be conducted away.

The openings 19, 20 and 21 are primarily intended for the purpose of cleaning the carbon deposits and sludge from the bottom 30 of the outer container. This may be accomplished by first withdrawing the liquid from the outer container by means of the outlet pipe 17, and then removing the closure plates of the openings 19, 20 and 21 and raking or sweeping out the carbon or sludge 35 from the bottom of the outer container, blowing it out by a sand blast or in any other suitable manner.

Attention is now directed to Fig. 5 of the 40 drawings which shows a set-up of the still illustrated in Figs. 1, 2 and 3 capable of being used for cracking or distillation or both of hydrocarbon compounds either at 45 atmospheric pressure or a pressure greater than atmospheric pressure according to the nature of the compounds to be treated and the character of the products desired. In this view, the still is shown mounted upon a suitable furnace setting 27 having a combustion chamber 28 and heated by a gas or oil burner 29. The apparatus is heated by the burner 29, and the hydrocarbon compounds to be treated are introduced into the still through the pipe 18. They pass successively through the series of cells as hereinbefore described, finally leaving the still through the outlet pipe 17. This pipe is continued and formed into a coil 30 surrounded by a jacket 31 and is cooled by water or other cooling medium, which enters the jacket through the pipe 32 and leaves through the pipe 33. In the coil 30, the pipe 17 is provided with a valve 34 for the purpose 55 of regulating the flow of the hydrocarbons

passing through the apparatus. A similar valve 35 is arranged in the pipe 17 beyond the jacket 31 to serve as a further convenience in regulating the flow of the hydrocarbons. The cooler just described is disclosed only for the purpose of illustration, it being understood that any other type of 70 cooler may be used.

The pipe 26 through which the vapors leave the still is divided into three branches 75 36, 37 and 38. Connected to the branch 36 is a pressure gauge 39, in the branch 37 is a release valve 40, and in the branch 38 is a regulating valve 41. This branch 38 leads into the interior of a reflux condenser 42. 80 The vapors which pass into the condenser 42 through the branch 38 are spread by the impingement cap 43 and passed through the tubes 44. The tubes 44 are cooled by water or oil entering at 45 and leaving at 46. The hydrocarbon vapors which enter the tubes 44 85 are partially condensed to liquid hydrocarbon compounds which flow from the condenser 42 by a pipe 47 which passes through the closure plate 25 of the opening 24 in the fixed head of the still and the end of the pipe 47 may be adjusted or extended to discharge into any selected chamber of the still. By this means, the higher boiling point constituents of the vapors are condensed and 90 returned to the still for further treatment. The vapors, however, leave the condenser by the pipe 48 leading to any desired type of condensing apparatus, not shown, where complete condensation takes place and the 95 final product is collected.

The apparatus illustrated in Fig. 5 is also suitable for the cracking of hydrocarbon compounds without separation of the low boiling point constituents formed by cracking. In this case, the valve 41 and the valve 100 49 arranged in the pipe 47, are closed, and the compounds after circulating through the still and passing through the pipe 17 are passed to a separate apparatus, not shown, 105 where separation of the low boiling point constituents is accomplished by distillation.

The routing of the hydrocarbons up and down and back and forth through the 110 sinuous passage of the still results in making the compounds travel through a considerably longer distance than in the usual cracking stills. The velocity of the hydrocarbons is also increased, all parts of the charge 115 are kept in a uniform state of motion, and the charge is progressively heated as it passes outward from the center of the apparatus to the outer side. The low boiling point constituents of the compounds are vaporized in a progressive manner as the charge works outward from the coolest zone in the center to the hottest zone at the outside. Thus, the danger of excessive frothing or hammering due to the water content 120 of the hydrocarbons being treated is eliminated.

nated, the progressive heating eliminating the water content and steam before the hottest zone is reached. The deposition of carbon or other solid matter in the apparatus is minimized by keeping all parts of the charge in both uniform and constant motion. The fouling of the bottom and sides of the outer container by carbon deposits is greatly minimized by the constant withdrawal of residual oil from intimate contact with the sides and bottom of the outer container. A uniform product is assured by the uniform heat treatment for a uniform interval of time and under constant pressure of each and every portion of the material treated.

While the apparatus shown in Fig. 5 is primarily intended to be used for continuous operation, it is equally well adapted for intermittent operation which is desirable on some distillates and residues. In using the apparatus for intermittent operation, the hydrocarbon compounds to be treated are fed into the apparatus by the pipe 18 and allowed to pass through the different cells until the inner container is filled and overflows into the space between the inner container and the outer container 1, and reaches the desired level in the outer container, it being understood that the valve 34 is closed. Heat is now applied to the outer container until the hydrocarbons in the still are sufficiently treated, the vapors being allowed to find exit through the pipe 26. The valve 34 is then opened and the space between the inner container and the outer container is drained of residual matter, after which a further quantity of hydrocarbon compound, equal in volume to the capacity of the space between the two chambers, are admitted by the pipe 18. This causes the heated compounds in the outer chamber of the inner container to overflow into the space between the two containers, and the cycle of operation is repeated. This method of operation is convenient when working residues inclined to the deposition of large amounts of carbon or sludge, and the bottom and sides of the outer container are kept clear by frequent removal of the entire residue. Any adhering deposits on the bottom or sides of the outer container may be removed through the openings 19, 20 and 21 as previously described.

Another useful feature of the invention is its adaptability as a topping apparatus for crude petroleum. For topping, the method of operation is the same as hereinbefore described in connection with cracking, except that the temperature of the apparatus is not maintained quite as high. A temperature just high enough to remove the natural gasoline from the oil is sufficient. The oil may be topped and cracked simultaneously, the topping taking place in the inner cham-

bers or cells and the cracking occurring in the outer cells where the temperature is the highest.

Attention is now directed to Fig. 6 of the drawings which represents a set-up of the apparatus capable of being used as a reaction or digestion chamber for hydrocarbons that have been heated in a separate apparatus. In this view, the still is shown as being placed upon the top of a furnace setting 27 provided with an enlarged combustion chamber 28' and heated by a gas or oil burner 29'. Arranged in the combustion chamber 28' so as to receive heat from the furnace is a coil 50. The hydrocarbons to be treated in the still are introduced into the coil 50 through a pipe 51 provided with the valve 52 and from the coil 50 the heated hydrocarbons pass into the pipe 18, which in this case is provided with a valve 53. In this type of apparatus, the still is not heated by the furnace which acts only as a means of support, but the hydrocarbons are heated entirely while in the coil 50. In this connection, it will be stated that the coil 50 has been shown and described as a convenient means of heating the hydrocarbons, but it is to be understood that other suitable heating means may be employed.

The method of using the still as a reaction chamber consists in opening the valve 52 and permitting the hydrocarbons to pass into the coil 50, where they are heated to the desired temperature by contact of the coil with the hot gases in the combustion chamber 28'. The flow of hydrocarbons through the coil 50 is controlled by the valve 53, and the hot hydrocarbons enter the chamber by the inlet pipe 18. After entering the container 1, which may now be termed a reaction chamber, the hot hydrocarbon compounds pass successively from the center outward through the series of cells, and after reaching the last cell, they are withdrawn through the pipe 17, the rate of flow being regulated by the valve 34. After passing through the valve 34, the compounds pass through the cooling coil 30 as hereinbefore described. In this form of apparatus, the heavy hydrocarbons may be cracked into lighter constituents by being allowed to remain in the apparatus at a sufficient degree of temperature for a sufficient period of time. The arrangement of the cells and concentric chambers causes the constant circulation of all parts of the charge and keeps the separated carbon and sludge in suspension and prevents the fouling of the apparatus with carbon deposits.

A further useful feature of the invention is its reversibility. In the embodiment hereinbefore described, the hydrocarbons are introduced into the center of the apparatus and in passing through the various cells work their way outward, leaving by the

outermost chamber, and in this form of apparatus, the wall of each inner chamber is slightly higher than the wall of the next outer chamber. It is equally practical, however, and in some cases desirable, to have the hydrocarbons enter the outermost chamber and leave by the innermost chamber. This can be accomplished by making the walls of each inner chamber or receptacle slightly lower than the walls of the next outer chamber. Such an arrangement is illustrated in Figs. 7 and 8 of the drawings.

In the embodiment of the invention illustrated in Figs. 7 and 8, the receptacles 6', 15 7' and 8' are disposed one within another and arranged in concentric relation, the walls of the receptacle 6' being higher than those of the receptacle 7', and the walls of the latter being higher than those of the 20 receptacle 8'. This form of apparatus is suitable for use in connection with a pump to promote rapid circulation of the charge. Such a pump is illustrated in Fig. 7. In this case, the outer container 1' is provided 25 at the top with an opening 54 closed by a closure plate 55, and supported by this plate within the container is the housing 56 of a submerged pump 57. The shaft of the pump 57 which is a centrifugal pump, extends upwardly through the housing 56 and plate 55 to suitable bearings 58 and 59 and is provided at its upper end with a pulley 60 to which power for driving the pump is supplied. Of course, any other suitable way 30 of driving the pump may be provided. As shown, the induction opening 61 of the pump is disposed in and close to the bottom of the inner receptacle 8', so that when the pump is in operation, the hydrocarbons in the receptacle 8' will be drawn out of the same. To 35 the ejection side of the pump, a pipe 62 is connected. This passes around the upper edges of all three receptacles and discharges into the space between the outer container 1' and the inner container. It will 40 thus be seen that by means of the pump, the hydrocarbons may be withdrawn from the inner chamber of the apparatus and discharged into the outer chamber.

In the form of apparatus illustrated in 45 Figs. 7 and 8, the inlet pipe 18' for the hydrocarbons discharges into the space between the outer container 1' and the inner container composed of the receptacles 6', 7' 50 and 8'. This form of apparatus still has the pipe 17 through which the carbon and residue in the outermost chamber may be drawn off, the vapor outlet pipe 26 having the branches 36, 37 and 38, the same as before. The branch 38 is of course connected 55 to a reflux condenser. This is not illustrated in Fig. 7, but it is to be understood that the branch 38 leads to one the same as shown in Fig. 5. In Fig. 7, the numeral 47' 60 represents a pipe corresponding to the pipe

47 of Fig. 5 which leads from the reflux condenser to the pipe 18'. This pipe 47' is provided for the purpose of returning the condensed hydrocarbons from the reflux condenser into the outer chamber of the apparatus. In this connection, it will be noted that the discharge end of the pipe 18' is disposed adjacent the discharge end of the pipe 62, so that the condensate returned from the reflux condenser will be intimately mixed with 75 the contents of the apparatus.

In using the type of apparatus shown in Figs. 7 and 8, the hydrocarbons are introduced by the pipe 18' until all of the chambers are filled, the charge flowing by gravity 80 from the outermost chamber to the innermost chamber. After the chambers have been filled, heat is applied and the pump is started. The pump keeps the entire charge in a constant state of motion by lifting it from the innermost chamber and conveying it to the outermost chamber, from which it returns to the innermost chamber by gravity. As the charge is heated, the lighter hydrocarbons and water are vaporized 85 and pass out through the vapor outlet pipe 26 and are lead by such pipe to the reflux condenser in which the heavier portions are condensed and returned by the pipe 47' and the pipe 18' into the apparatus for 90 further treatment. This procedure is continued until the level of the hydrocarbons in the apparatus is sufficiently reduced to require a further quantity of hydrocarbon 95 compounds to be introduced, which is of course done and the operation is allowed to 100 continue. When a sufficient quantity of hydrocarbons have been worked to cause the accumulation of considerable carbon or other residue, the outermost chamber should 105 be emptied by the pipe 17, and after this has been done, fresh material should be introduced by the pipe 18' and operation should be resumed as already described.

From the foregoing description taken in 110 connection with the accompanying drawings, the construction, operation, use and advantages of the invention will be understood by those skilled in the art to which the invention appertains to enable them to make use 115 of the same. Further description is therefore thought to be unnecessary, but it is desirable to mention that the invention is adaptable to the conventional form of still now in general use, for by the removal of 120 the head of any conventional type of still, an inner container such as hereinbefore described may be installed so as to convert the plain type of still into one of the types disclosed herein.

125 It is obvious that numerous changes in form, proportion, and the details of construction, may be made without departing from the spirit and principle of the invention and without sacrificing any of the ad- 130

vantages thereof, so that it is to be understood that such may be done within the meaning and scope of the appended claims.

What is claimed is:—

5. 1. An apparatus for the treatment of hydrocarbon compounds comprising an outer container, an inner container within the outer container and spaced therefrom, the bottom of the inner container having a partition member connected to the bottom of the outer container by a liquid-tight joint, said joint including a fusible substance of higher specific gravity than and non-miscible with the substance to be treated in the apparatus.
10. 2. An apparatus for the treatment of hydrocarbon compounds comprising a container having a plurality of concentrically arranged receptacles dividing the interior of the container into a series of concentric chambers, a plurality of transverse partitions in said chambers dividing the latter into a series of communicating cells, and means establishing communication between said cells, said means being arranged in staggered relation so that the hydrocarbon compounds will flow alternately up and down in passing through the series of cells and whereby said compounds will flow from the central chamber outwardly.
15. 3. An apparatus for the treatment of hydrocarbon compounds comprising an externally heated outer container, an inner container within the outer container and spaced therefrom, said inner container having a partition member connected to the outer container throughout the length of the bottom and the height of one end of said inner con-
40. tainer by a liquid-tight joint, an inlet into the inner container and an outlet from the space between the inner container and the outer container, whereby the hydrocarbon compounds flowing from the inner container into the space between the outer container and the inner container are caused to flow around the inner container before passing from the apparatus.
45. 4. An apparatus for the treatment of hydrocarbon compounds comprising an outer container provided with a plurality of concentric receptacles dividing the interior of the container into a plurality of concentric chambers, a plurality of transverse partitions in the chambers dividing the latter into a series of charge receiving communicating cells through which the charge will flow from the central chamber outwardly, an inlet into the first cell of the innermost chamber, and an outlet from the last cell of the outermost chamber.
50. 5. An apparatus for the treatment of hydrocarbon compounds comprising an externally heated container divided into a plurality of concentric charge receiving communicating chambers, an inlet into the innermost chamber and an outlet from the outermost chamber, said container being provided with a vapor outlet, a reflux condenser arranged to receive the vapors from said vapor outlet, and adjustable means for conveying the condensate from said reflux condenser to a selected one of said chambers.
55. 6. In testimony whereof I have hereunto affixed my signature.

EARL R. HAMILTON.
